UNITED STATES PATENT OFFICE.

JAMES H. BIGALOW, OF RAVENNA, OHIO.

DESIGN FOR A TOY BANK.

No. 39,644.

Specification for Design.

Patented Oct. 27, 1908.

Application filed August 3, 1908. Serial No. 446,819. Term of patent 14 years.

To all whom it may concern:

Be it known that I, JAMES H. BIGALOW, a citizen of the United States of America, residing at Ravenna, in the county of Portage and State of Ohio, have invented a new, original, and ornamental Design for a Toy Bank, of which the following is a specification, reference being had to the accompanying drawing, forming part thereof.

In the drawings Figure 1 is a front elevation of a toy-bank embodying my ornamental design. Fig. 2 is a side elevation of same.

I claim:

The ornamental design for a toy-bank as shown.

JAMES H. BIGALOW.
